UNITED STATES PATENT OFFICE.

CHARLES A. LIEB, OF NEW YORK, N. Y., ASSIGNOR TO ZINN & KAYSER, OF SAME PLACE.

GRAIN-WEIGHING SCALE.

SPECIFICATION forming part of Letters Patent No. 368,840, dated August 23, 1887.

Application filed November 13, 1886. Serial No. 218,788. (No model.)

To all whom it may concern:

Be it known that I, CHARLES A. LIEB, a citizen of the United States, residing at New York, in the county and State of New York, 5 have invented new and useful Improvements in Weighing-Scales, of which the following is a specification.

This invention relates to improvements in automatic scales; and it consists in the features 10 set forth in the following specification and claims, and illustrated in the accompanying drawings, in which—

Figure 1 is a side elevation, partly in section, of a scale containing my invention. 15 Fig. 2 is a section in the plane $x-x$, Fig. 1. Fig. 3 is a section in the plane $y-y$, Fig. 1. Fig. 4 is a section in the plane $z-z$, Fig. 1. Fig. 5 is a detail view of parts of detent-levers and adjacent mechanism.

20 Similar letters indicate corresponding parts. A is the side frame of the machine, and B is the top frame. A hopper, D, is suitably attached or fixed to the device—as, for example, by arms or braces J rising from the top frame, 25 B. The hopper D leads the material to be weighed—such, for example, as grain—into an oscillating box, L. The oscillating box L is supported by pivots n' on the uprights n . The uprights n depend from a frame, m, which 30 rests on a knife-edge, l.

The bearing-surfaces of the frame m which come into contact with the knife-edge l are formed on lugs or pieces a. By having the pieces a removably attached to the frame m—35 as, for example, by screws—said bearing lugs or pieces a can be removed when worn or frayed. The knife-edge l rests upon the forked scale-beam H. The knife-edge l is conveniently formed by properly shaping a rod or 40 bar of suitable material—such as steel—and resting said rod or bar upon suitable bearings on the scale-beam H.

The scale-beam H oscillates upon the knife-edge g, which knife-edge can be conveniently 45 formed by a properly-shaped rod or bar resting on suitable bearings on the top frame, B. The bearing-surfaces of the scale-beam which come into contact with the knife-edge g are formed on lugs or pieces b. By having the 50 lugs or pieces b removably attached to the

beam H—as, for example, by screws—said bearing lugs or pieces b can be removed when worn or frayed.

Passages or openings c d are formed through the hopper D for the insertion and withdrawal 55 of the knife-edges g l. Suitable hoods or covers surround the channels or openings c d, to prevent any material passing through the hopper from striking the fulcrum or knife-edges g l. It is also to be noticed that by making the 60 lugs or bearing-surfaces a b in the shape of suitable rods or bars, which rest along their length upon the knife-edge bars g l, the strain or wear produced by the oscillation of the beam H will not be allowed to bear only on a 65 few isolated points, but said wear and friction will be distributed along certain lines. The wear and strain at any one point are thus diminished. The bearing-surfaces may either be fixed to or removably formed along the 70 rods, arms, or bearings k o of the beam H and frame m, and the lugs or projections a b, besides being mere bearing-surfaces, can be advantageously made to overlap or partly overlap the knife-edge bars g l, so as to prevent 75 lateral motion of the beam H and frame m on the knife-edges g l.

The weighing-box L is divided by a partition, N, into two compartments, and by the movements of the box L the said compartments 80 are alternately brought into communication with the hopper D. The compartments are provided with movable bottoms O O', hinged or movably attached to the box, as shown. In the drawings the bottom O' is shown as 85 closed and its compartment as being in communication with the hopper.

To the arm I of the scale-beam is attached a weight, W, and when the quantity of material—such as grain—which has been fed onto the 90 bottom O' is sufficient to overbalance the weight W the beam H will oscillate and the box L will descend. The weight W, as seen, is preferable mounted upon an arm, K, rising from a pivot, M, which connects said arm K to the 95 arm I. The position of the weight is such that on the downward movement of the box L the weight W is rapidly oscillated or moved toward the vertical plane passing lengthwise through the knife-edge g. The effect of the 100

weight W on the box L is thus rapidly diminished as soon as the downward motion of the box L has commenced.

To one of the uprights n are pivoted detent-levers S S' by suitable pivots, Y Y'. The pivots Y Y' are formed in a suitable bearing or bearings, r, attached to an upright n. To the box L are pivoted rollers X X by suitable pivots, p, having bearings in arms q, connected to the side of the box. In the drawings one of the rollers X is shown as in engagement with a detent-notch in the detent-lever S, whereby the box L is held in the position shown in Fig. 2, with the bottom O' closed. When the box L descends, the hanger T lifts the lever S out of engagement with the roller X, when the weight of the material at one side of the box L, and which presses upon the bottom O', causes the box to oscillate about the pivots n', so that the bottom O' is carried away from the roller P', which before pressed or held the bottom O' shut. The bottom O' is now allowed to open and the material discharges. By this motion of the box L the bottom O is closed, the detent-lever S' is caused to engage the other roller X, and the operation which has just been described in connection with the compartment having the bottom O' is now repeated with the compartment having the bottom O. These oscillations of the box L may be registered on any suitable counting device or register.

The hangers T T depend from the top frame, B, and their set-screws V V' are adapted to lift the levers S S' out of engagement with the rollers X X. The rollers P P', which close the bottoms O O', are adjustable on the upright n. This adjustability of the rollers P P' can be attained by the means shown in the drawings, where said rollers P P' are mounted on arms R R, which are adjustably connected to the uprights n, or to arms s, connected to the uprights n. By slotting the arms R and passing set-screws j through the slots into the arms s said arms R can be adjusted along the slots as desired.

The material discharging from the box L strikes a ridge-plate, E, connected to a lever, F, having a counter-balance, G. The material striking the ridge-plate E causes the lever F to oscillate so as to actuate the rod U, which connects by a crank-arm with the hopper-valve Q, thus closing the valve Q during the shifting of the compartments of the box L.

The weight W is made adjustable. A convenient means of adjustment of the weight is shown in the drawings, where the weight-arm K is provided with an arm or arms, e e, provided with set-screws f. These set-screws f strike against the arm I and hold the weight W in a fixed position relatively to the arm I. By properly operating the screws f the inclination of the weight-arm K to the beam-arm I is varied, thus varying the effect of the weight W upon the box L.

The oscillations of the beam-arm I can be limited by a set-screw, i, in the frame A. When

at rest, the beam-arm I rests on the lug or arm h of the frame A. The oscillations of the beam-arm I can thus be limited so as to confine the oscillations to secure rapid operation of the device, while at the same time the oscillations of the beam-arm I can be allowed to have sufficient scope to secure perfect operation of the device.

The device can be made of any suitable material—such, for example, as iron or steel. As considerable strain is brought upon the fulcrum or turning-points l g and the contact-surfaces a b, and the contact-surfaces of the bars or arms k o, it is well to make these parts of very hard and durable material—such as a superior kind of steel—which will resist wear, and which can also be polished, so as to diminish friction; also, the removability of these parts or bearing-surfaces a b g l and of the bearing-surfaces of the arms or bars k o allows the same to be replaced by new parts whenever requisite, while the rest of the device may be left intact. The pivots n' should be so placed that the two compartments of the box L when the box is empty will be evenly balanced.

The device may be modified, if desired. For example, in place of two adjusting-screws f pressing onto the arm I, one adjusting-screw may be made to answer by having said screw firmly connected to the arm I, said screw being only left free to turn in said arm. Such turning of the screw will then move the weight-arm K about the pivot M; or the arm K, instead of being movable on a pivot M, may be caused to move or slide along the arm I.

In the drawings is shown an automatic scale; but it is evident that a knife-edge bar such as the bar g and a bearing surface or bar engaging the knife-edge bar along the lengths of the knife-edge bar and the bearing-bar can be applied to any scale, and such arrangement serves to diminish wear of the knife-edge and bearing-surface. It is also evident that the bearing-bar can be made to rest upon the knife-edge bar, or the knife-edge bar upon the bearing-bar, as desired, so that either the bearing-bar bears upon the knife-edge bar or the knife-edge bar bears upon the bearing-bar.

As seen in Figs. 4 and 5, the detent-levers S S' are pivoted independently of one another, so as not to rub or chafe against one another and to prevent dust or other foreign matter from lodging between said levers, as might occur if said levers were pivoted to a common pivot instead of to the separate pivots Y Y'. It is also to be noticed that said detent-levers S S' are pivoted on centers—that is, on points Y Y' entering grooves or recesses Y' in said levers. The levers are thus enabled to operate easily and with little friction, and any dust or impurity that lodges on the points or centers Y' will easily pass off said centers, because of the inclined character of such centers and of their engaging-recesses Y'. It should be noticed that the pivots n', supporting the weighing-box L, also form points or centers,

thus securing an easy oscillation of the box L, as said points or centers have free play in recesses in the box L, with which recesses said centers are in engagement.

5 What I claim as new, and desire to secure by Letters Patent, is—

1. The combination, with the pivoted weighing-box L, of the beam H, beam-arm I, the arm K, rising from the arm I and having 10 pivotal adjustment thereon, and the weight W, carried by arm K, substantially as described.

2. The combination, with the pivoted weighing-box L, of the beam H, beam-arm I, the arm K, rising from and pivotally adjustable 15 upon the arm I, the adjusting-screws f f, tapped through lugs on said arm K and bearing on the beam-arm I, and the weight W, substantially as described.

3. The combination, with the pivoted weighing-box L, of the beam H, weight W, and 20 knife-edge bars g l, substantially as set forth.

4. The combination, with the pivoted weighing-box L, of the beam H, weight W, and removable knife-edge bars g l, substantially as 25 set forth.

5. The combination, with the pivoted weighing-box L, of the supporting-frame m, knife-edge bar l, beam H, knife-edge bar g, and weight W, substantially as set forth.

30 6. The weighing-box L, combined with the uprights n, movable bottoms O O', and adjustable rollers P P', substantially as set forth.

7. The combination, with the weighing-box L and hopper D, of the beam H, weight W, pivots or fulcra g l, and chambers or recesses 35 c d in the hopper, substantially as set forth.

8. The combination, with a scale-beam provided with a knife-edge bar and a bearing surface or bar, said bars being in engagement with one another throughout their respective 40 lengths, of a second knife-edge bar, l, and bearing surface or bar supported on said scale-beam, and being in engagement with one another throughout their respective lengths, said knife-edges and bearings extending from side 45 to side of the machine, substantially as set forth.

9. The combination, with the oscillating box L, having hinged bottoms O O', of the adjustable rollers P P', substantially as described. 50

10. The combination, with the oscillating box L, pivoted on centers n' and having the hinged bottoms O O', of the rollers P P', journaled on the slotted adjustable arms R, and set-screws j, passing through said slots, substantially as described. 55

In testimony whereof I have hereunto set my hand and seal in the presence of two subscribing witnesses.
